UNITED STATES PATENT OFFICE.

WARREN B. FLANDERS, OF WILKINSBURG, PENNSYLVANIA, ASSIGNOR TO WESTINGHOUSE ELECTRIC & MANUFACTURING COMPANY, A CORPORATION OF PENNSYLVANIA.

BLADE.

1,290,533.

Specification of Letters Patent.

Patented Jan. 7, 1919.

Application filed April 14, 1917. Serial No. 162,020.

To all whom it may concern:

Be it known that I, WARREN B. FLANDERS, a citizen of the United States, and a resident of Wilkinsburg, in the county of Allegheny 5 and State of Pennsylvania, have made a new and useful Invention in Blades, of which the following is a specification.

This invention relates to blades and has for an object to produce an improved form 10 of blading especially adapted to be employed in turbines.

A further object is to produce a new and improved combination ahead and reversing blade.

15 A further object is to produce a blade having a combination shroud and auxiliary bucket member formed on one end thereof.

A further object is to produce a blade 20 which is especially adapted to be employed in reversible turbines.

25 These and other objects which will be made apparent throughout the further description of my invention are attained by means of blading embodying the features herein described and illustrated in the drawings accompanying and forming a part hereof.

It is common in marine turbine installations to employ either a separate turbine or 30 separate turbine wheels and their blades for reversing operation. Double decked blades have also been employed for the purpose of eliminating the necessity of employing either a separate reversing turbine or separate reversing wheels.

35 In the old forms of double deck blades the working surfaces of both decks are of substantially the same construction but face in opposite directions. My invention comprises a new and improved 40 double decked blade which has the advantages of compactness and increased strength over the old forms of double decked blades.

While the blades illustrated are adapted for use as combined ahead and reversing turbine blades, it will be apparent that the invention broadly contemplates a multiple blade in which both working portions may be employed simultaneously, or in which one working portion is in operation only when 45 the other is not in operation.

As illustrated, my invention consists in providing a row of auxiliary buckets of the peripheral or Pelton type, on the outer ends of an assembled row of blades. The auxiliary buckets are illustrated as reversing 50

buckets and are formed in the shroud members of the blades, or so formed that they form a shroud for the assembled rows of blades. By means of my invention I produce a double decked blade, which is but 60 slightly larger than the ordinary shrouded impulse blade, and with which a reversible turbine may be constructed without the necessity of employing separate blade wheels for reversing purposes. 65

In the drawings: Figure 1 is a perspective view of a blade embodying my invention.

Fig. 2 is a sectional view of a number of blades assembled in a row. 70

Fig. 3 is a perspective view of the blades shown in Fig. 2.

The blade illustrated in Fig. 1 comprises a body portion 5 having a mounting shank 6 formed on one end thereof and a shroud member 7 formed on the other end. The shank 6 is adapted to engage a blade mounting element and to be secured thereto by rivets or any other blade securing means. In this embodiment of my invention the 80 body portion 5 of the blade is of the familiar impulse type. Impulse blades give the highest efficiency when they are shrouded so as to prevent leakage around the ends of the blades. For this reason, I have enlarged 85 the shank 6 of the blade so as to form an inner shroud member 8 which is adapted to fit against the face of an adjacent blade as shown in Figs. 2 and 3. The outer shroud member 7 is also adapted to fit against the 90 face of an adjacent blade so that steam passages 9, walled in on all four sides, are provided between each two blades. The face of the blade body is, of course, formed to extract the velocity energy of the steam 95 passing through the passage 9.

The outer shroud member 7 is made somewhat deeper than usual and, as shown, has formed in its outer portion a bucket 10 of the peripheral or Pelton type. These 100 buckets are substantially circular in plan and are obliquely disposed so as to overlap each other. They are adapted to receive steam from a nozzle having its axis substantially in the plane of the blade carrying element but located beyond the blades and inclined at an acute angle to the periphery of the shroud formed by shroud members. A lip 11 on each blade forms, on one side, the 105

110 roof of the bucket 10, formed in the shroud

member 7 of that blade, and on the other side, an extension of the floor of the bucket formed in the shroud member on one of the adjacent blades. This is well shown in Figs. 5 2 and 3. When the blades are in the assembled position the upper surface of the lip 11 of each blade lines up with the top of the shroud member 7 of an adjacent blade so as to form a continuation of the floor 12 of the 10 bucket 10 formed in the other adjacent blade. The side walls 13 of the lip 11 and the buckets 10 are adapted to coöperate as shown so as to form smooth and continuous lateral shrouds for the buckets 10. These walls 15 form the lateral faces of the peripheral shroud of the blades 5. As shown in the drawings there is one bucket 10 formed on each blade but obviously the number of buckets may be either increased or decreased 20 without departing from the spirit and scope of my invention. Furthermore, if the buckets are milled in the solid blade shroud after the blades are assembled the pitch of the buckets need bear no relation to the pitch 25 of the blades inside of the shroud. As is well known to those skilled in the art buckets such as those illustrated are commonly milled in the solid periphery of a rotor wheel. By providing a somewhat heavier 30 shroud on the blades than has commonly been provided I produce a surface on the outside of ordinary blades which may be milled to form the buckets 10 in the ordinary manner. Obviously these buckets may also 35 be formed in casting, forging or milling the individual blades.

Although I have somewhat increased the depth of the shroud on the blade bodies 5, a large portion of this shroud is cut away, 40 due to the buckets formed therein, consequently I have added substantially nothing to the weight of the blade and have increased its length but slightly. For these reasons blades built in accordance with my 45 invention give no trouble from excess weight, length, or objectionable vibrations.

Although I have shown the buckets 8 as facing in the opposite direction from the major portion of the blade, it is evident that 50 they may equally well face the other way. They could then be employed for light loads or in augmenting the power of the turbine under overloads, or in series with the blades 5.

While I have illustrated and described 55 but one embodiment of my invention, it will be apparent to those skilled in the art that various changes, modifications, omissions and additions may be made in the blade 60 illustrated without departing from the spirit and scope of the invention as set forth by the appended claims.

What I claim is:

1. As an article of manufacture, a blade 65 having a portion thereof formed to operate

on motive fluid delivered to it in a transverse direction, and a portion on one end formed to operate on motive fluid delivered to it from a point beyond the end of the blade. 70

2. As an article of manufacture, a blade having a portion thereof formed to operate on motive fluid delivered to it in a transverse direction, and a portion on one end formed to operate on motive fluid delivered to it 75 from a point beyond the end of the blade, said portions being arranged to produce motion in opposite directions.

3. A turbine blade having a longitudinally-extending transversely-curved working surface for receiving motive fluid delivered to it from one side of the blade, and an inclined bucket formed on one end of the blade for receiving motive fluid delivered to it from a point beyond the end of 80 the blade. 85

4. A turbine blade having a longitudinally extending working surface for receiving motive fluid delivered to it from one side of the blade, a shroud member formed 90 on the outer end of the blade, and a bucket formed in the shroud member for receiving motive fluid delivered to it from a point beyond the end of the blade. 95

5. A turbine blade having a body portion 95 for operating on motive fluid delivered to the blade from one side thereof, and a shroud member formed on the free end of the blade and adapted to coöperate with similar members of adjacent blades to form 100 a continuous shroud around the free ends of the blades, said shroud member including parts of buckets in its outer portion so as to form a continuous row of buckets in the shroud when in the coöperating position. 105

6. In a turbine blade, a blade body, and a bucket formed on the outer end thereof for operating on motive fluid delivered to said bucket in an inclined direction in a plane substantially perpendicular to the plane of 110 the stream of motive fluid passing through the blade body.

7. A blade having a body portion of the impulse type and a bucket of substantially the Pelton type formed on one end thereof. 115

8. Turbine blading comprising end supported blades, shrouded at the free ends, and impulse buckets formed in the peripheral face of the shroud.

9. Turbine blading comprising end supported blades mounted in a row, a shroud for the free ends of the blades and peripheral buckets so formed in said shroud as to be shrouded by the lateral portions thereof. 120

10. Turbine blading comprising end supported blades mounted in a row, a shroud member formed at the free end of each blade, and coöperating with adjacent shroud members to form a shroud for the row, and peripheral buckets formed in said shroud. 125 130

11. Turbine blading comprising end supported blades mounted in a row, a shroud for the free ends of the blades, and inclined peripheral buckets formed in said shroud and located in overlapping relation.

12. Turbine blading comprising end supported blades mounted in a row, a shroud member formed at the outer end of each blade, and a portion of two peripheral buckets formed in each shroud member, said

shroud members coöperating to form a shroud for the row of blades, and a row of peripheral buckets.

In testimony whereof, I have hereunto subscribed my name this tenth day of April, 15
1917.

WARREN B. FLANDERS.
